(57) **CLAIM**

The ornamental design for a glove, as shown and described.

DESCRIPTION

FIG. 1 is a perspective view of a first embodiment of a glove, according to our new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a perspective view of a second embodiment of a glove;

FIG. 9 is a left side view thereof;

FIG. 10 is a right side view thereof;

FIG. 11 is a front view thereof;

FIG. 12 is a rear view thereof;

FIG. 13 is a top view thereof; and

FIG. 14 is a bottom view thereof.

FIG. 15 is a perspective view of a third embodiment of a glove, according to our new design;

FIG. 16 is a left side view thereof;

FIG. 17 is a right side view thereof;

FIG. 18 is a front view thereof;

FIG. 19 is a rear view thereof;

FIG. 20 is a top view thereof;

FIG. 21 is a bottom view thereof;

FIG. 22 is a perspective view of a fourth embodiment of a glove, according to our new design;

FIG. 23 is a left side view thereof;

FIG. 24 is a right side view thereof;

FIG. 25 is a front view thereof;

FIG. 26 is a rear view thereof;

FIG. 27 is a top view thereof;

FIG. 28 is a bottom view thereof;

FIG. 29 is a perspective view of a fifth embodiment of a glove, according to our new design;

FIG. 30 is a left side view thereof;

FIG. 31 is a right side view thereof;

FIG. 32 is a front view thereof;

(Continued)

FIG. 33 is a rear view thereof;
 FIG. 34 is a top view thereof; and,
 FIG. 35 is a bottom view thereof.
 The broken lines in the drawings illustrate portions of the
 glove that form no part of the claimed design.

1 Claim, 30 Drawing Sheets
